UNITED STATES PATENT OFFICE.

JOHN CAMIDGE, OF BOWMANVILLE, ONTARIO, CANADA.

ORGAN-COUPLER.

SPECIFICATION forming part of Letters Patent No. 251,027, dated December 20, 1881.

Application filed July 27, 1881. (No model.)

To all whom it may concern:

Be it known that I, JOHN CAMIDGE, of Bowmanville, in the county of Durham, in the Province of Ontario, in the Dominion of Canada, 5 have invented certain new and useful Improvements in Organ-Couplers; and I do hereby declare that the following is a full, clear, and exact description of the same.

Figure 1 is an elevation. Fig. 2 is a plan, 10 and Fig. 3 is a vertical section on line *a a* of Fig. 2.

The invention consists, in combination with other elements, as hereinafter described and claimed, of a coupler whereby, when playing, 15 say, three notes with one hand only, the octave of the lowest note shall be coupled—that is to say, the octaves of the two higher notes shall be uncoupled—the object of the invention being to prevent disagreeably “thickening” the harmony by the multiplication of sounding octaves.

20 A are the keys of the manual, bearing on the inclined end of a coupler-lever, B, rocking between fulcrums *a a* to lift the opposite end of the lever by the depression of the key, and 25 which end operates the escapement hereinafter described to open the valve of the note to be sounded by lifting the connecting-bar C, arranged in the ordinary manner.

The escapement is composed of a series of 30 flat levers, D, of the form of an inverted T, placed laterally apart, one end fulcrumed to brackets F, corresponding in number to the number of levers, which levers have a vertical movement, the free end being lifted by the free 35 end of lever B.

G are fixed brackets, each supporting a lever, H, pivotally connected at the ends, said lever having a free end which is bent or formed at right angle to have contact with the vertical 40 arm of levers D, and which levers H are kept by a spring, I, in position to yield to the action of lever D when raised by lever B.

The levers H have each a projection, J, which bears against the edge of the preceding lever, 45 whereby a continuous section or series of levers will be simultaneously moved, the portion or section of the same below the lever moved remaining stationary.

50 By this invention, when the “octave-coupler” (coupling down) stop is drawn, the lowest key pressed in the bass releases from the operation

of the coupler any key that may be under pressure higher up toward middle C, thus making the octave of the lowest key under pressure the real fundamental note sounded. By reversing the coupling-lever and mechanism to couple up, similar results are obtained in the treble, where by the use of this invention only the top note under pressure, whatever it may be, would sound its octave above. 60

The levers D support pitmen K, one end bent to a double-crank form to connect loosely with levers D laterally, and which pitmen pass freely through a hole in levers H.

L are spiral springs connecting with the 65 crank of pitmen K and the outer extremity of levers D, the contraction of the spring returning the pitman to a vertical position after being thrown to an inclined position by the inward movement of levers H. 70

In ordinary cases of coupling, three keys struck with one hand would sound six notes. With the coupler herein described only four notes would sound. Thus in playing the common chord of G with the left hand, the thumb 75 depressing G, first line, the fourth finger the octave lower, the octaves of B and D used in the chord would be released and only the octave of the lower G sounded. The coupler-lever B and the other levers connect the key A with 80 its valve-bar, and by operation disconnect the valve-bars from operation by their respective levers, so that when the A note is depressed, supposing it to be the lowest note struck, A will sound and also its octave, and all the notes 85 between A and its octave will not be affected by the coupler, thus making the octave of the lowest key the real fundamental note sounded, thereby improving the harmony, which is now impaired by the sound of the intermediate 90 coupled octaves. When too many notes sound harmony is thickened. The strength lies in the octave of the lowest note played with the left hand and the octave of the highest note of the right hand. 95

In an organ without a coupler the foot-pedal is used to sound the one note which I now sound with the finger, and in organs with couplers each note, roughly speaking, is coupled to its own octave, and thereby too many notes 100 sound. In the coupler herein described, if more than one key is depressed with one hand, only

one coupled note is sounded, and that one the lowest played with the left hand or the highest with the right hand.

The operation is as follows: Referring to 5 the bass of the manual, the lowest key being depressed, its lever B will lift its lever D and pitman K vertically, the pitman thereby opening its valve-bar C, and at the same time the lever D will move inwardly all the levers H 10 above it, thereby inclining the pitmen free from the ends of the bars C. The springs L assist to bring the pitmen vertically under the bars C when the pressure on the lowest key struck is released.

15 It is obvious that, after the ends of the pitmen have been carried clear of the ends of bars C by the combined inward movement of levers H, depression of any of the keys above the lowest one struck will produce no movement of the bars C, and therefore the notes 20 will not be sounded.

I have herein described my device as applied to the bass; but by reversing the levers B it can be applied likewise to the treble. This 25 escapement can be used under the front, also on the top, as well as at the back of the keys, with the same effects as represented in the drawings. In the upper octave of the bass-register,

in which middle C is the top note, any key or collection of keys put down, the lowest key 30 alone takes its octave-key below and releases all the others. In reversing the levers and mechanism an opposite result would be obtained—the top or treble key would take its octave above and let off all the others. 35

I claim as my invention—

In combination with the key-board of an organ, the coupler-levers B, pivoted levers H, having projections J, levers D, provided with pitmen K, passing through levers H, and the 40 valve-bars C, all constructed and arranged substantially as described, whereby, in playing several keys of the key-board at the same time, the coupler-lever of the lowest bass-key or of the highest treble-key will operate its valve-bar, but will displace or cause an escapement of all the pitmen of the valve-bars of the others above or below, as the case may be, so that the lowest bass-note or highest treble-note only of the series will be coupled and the others 45 50 sounded singly.

JOHN CAMIDGE.
